US00D628507S

(12) **United States Design Patent**
Plange

(10) **Patent No.:** **US D628,507 S**
(45) **Date of Patent:** **** Dec. 7, 2010**

(54) **DIAL**

(75) Inventor: **Gerd Plange**, Beringen (CH)

(73) Assignee: **Richemont International SA**,
Villars-sur-Glane (CH)

(**) Term: **14 Years**

(21) Appl. No.: **29/365,544**

(22) Filed: **Jul. 9, 2010**

(30) **Foreign Application Priority Data**

Jan. 15, 2010 (WO) DM/072 905

(51) **LOC (9) Cl.** **10-07**

(52) **U.S. Cl.** **D10/126**

(58) **Field of Classification Search** D10/30-39,
D10/122-126, 6, 10; 368/80, 223, 228, 232,
368/28

See application file for complete search history.
